ELECTRICAL DEEPWELL PUMP

Philip W. Martin, Huntington Park, Calif.

Application November 12, 1946, Serial No. 709,173

8 Claims. (Cl. 103—46)

1

My invention relates to the art of pumping fluids from wells and relates in particular to a simple electrically operated pumping device having special utility as a means for pumping oil from deep wells.

It is an object of the invention to provide a reciprocating pump adapted to be installed in a well and means for operating this reciprocating pump, consisting of a simple reciprocating electric motor operated by electric current received from an electrical power source at the top of the well.

It is an object of the invention to provide a simple pumping device to replace pumping devices of the types now commonly employed. The most common is the reciprocating pump operated by sucker rods. This type of pumping equipment has a number of disadvantages which are avoided by the present invention. Not only do the thousands of feet of sucker rods required for the operation of the pump piston constitute a major item of expense, but the use of these sucker rods results in a great power loss from friction and from the power expended in stretching the sucker rod string during each pumping stroke. A further disadvantage avoided by the present invention is that the wearing of the oil tubing by the moving sucker rods is avoided. The present invention has no reciprocating parts which could wear holes through the tubing as sometimes occurs in the use of sucker rod operated pumps.

Another object of the invention is to provide a simple electrically operated pumping device which will avoid many of the difficulties encountered in the use of electrical and hydraulic pumping systems.

It is an object of the invention to provide a pumping unit adapted to be connected to the lower end of an oil tube which is suspended in the well, this pumping unit comprising a pump and an electric motor which is connected in series with the oil tube and with the casing of the well, thereby avoiding the need for separate electrical conductors in the well for carrying electric power to the motor.

In the practice of the invention the tubing is insulated from the casing by use of rubber tubing protectors which hold the tubing in spaced relation to the casing. If necessary, the lower portion of the tubing and the pump unit which extend into liquid in the well may be coated with insulating material of the type adapted to be sprayed thereon just before the pumping unit and the tubing are lowered into the well.

An important object of the invention is to provide a simple pumping device having a pump unit adapted to be placed in the well, this unit comprising a reciprocating pump driven by a reciprocating electrical motor. Although I operate

2

this motor by current which passes through the oil tube and through the casing, it is not essential to all practices of my invention that the oil tube be used as a conductor to carry power to the motor. Accordingly, it will be understood that if desired, the pump unit may be operated in the well by power carried thereto through insulated electrical cable means.

Further objects and advantages of the invention may be brought out in the following part of the specification wherein specific explanation is employed for the purpose of fully disclosing a preferred embodiment of the invention without placing limitations on the scope of the invention set forth in the appended claims.

Referring to the drawings which are for illustrative purposes only,

Fig. 1 is a schematic elevational view showing a preferred embodiment of the invention disposed in a well.

Fig. 2 is an enlarged fragmentary section showing a tubing insulator such as employed in the tubing string shown in Fig. 1.

Fig. 3 is an enlarged fragmentary sectional view showing a portion of the casing of Fig. 1 and the pumping unit thereof.

In Fig. 1 I show a well 10 lined with a pipe string casing 11 which has perforations 12 near its lower end for admitting oil into the well from the adjacent formation 13, the oil level in the well being indicated at 14. In the oil a pump unit 15 of my present invention is suspended by a string of tubing 16. The tubing string consists of a plurality of upper tube sections 17 connected by couplings 18 and one or more lower tube sections 19 disposed between the lower end of the assembly of upper sections 17 and the upper end of the pump unit 15, the tube section 19 being connected to the lowermost of the tube sections 17 by an insulating connector 20 constructed as shown in Fig. 2.

The insulator connector 20 includes sleeves 21 and 22 for insulating the upper end of the tube section 19 from the lower end of the tube section 17 shown in Fig. 2. The insulating sleeve 21 fits around the upper end of the tube 19 and engages the lower face of a collar 23 which is threaded onto the upper end of the tube 19. At a plane disposed below the collar 23 the insulating sleeve 21 is diametrically reduced so as to provide a downwardly faced annular shoulder 24. The upper insulated sleeve 22 fits between the ends of the tube sections 17 and 19 and has its lower end counterbored so as to provide a wall 25 surrounding the collar 23. The parts disclosed with relation to Fig. 2 are held together by a cylindric shell 26 which surrounds a portion of the insulator 21 and has an upwardly faced shoulder 27 to engage the shoulder 24. The shell 26 extends upwardly across the outer face of the insulator

22 and across a collar 28 which is threaded onto the lower end of the tubing section 17, the upper end of this shell 26 being equipped with internal threads 29 to receive a bushing 30, the lower end of which bushing 30 bears against the upper face of the collar 28 while, at the same time, pulling upwardly on the shell 26 and thereby axially compressing the insulator members 21 and 22 and rigidly connecting the tube sections 17 and 19 together.

As shown in Fig. 3, the pump unit 15 includes a reciprocating pump 31 and a reciprocating electric motor 32 having thereon bow springs 33 which bear against the inner surface of the casing 11 in a manner to make electrical contact therewith. The pump 31 projects upwardly from the motor 32 and has its outlet end 34 connected to the lower end of the tube section 19 by means of a bushing 35 which is internally threaded so that it may be screwed onto the lower end of the part 19. The reciprocating pump 31 includes a casing or cylinder 36 having near its lower end an oil inlet opening 37. Sealing means are provided in the lower part of the cylinder 36 below the opening 37, these sealing means being shown as annular sealing members 38 arranged to engage the external surface of a plunger 39, the lower end of which extends down into the motor 32 so as to be vertically reciprocated by the moving parts of such motor.

Above the opening 37, the cylinder 36 has therein annular sealing members 40 engaging the external surface of the plunger 39 and preventing leakage of fluid downwardly around the exterior of the plunger 39 from the pumping space 41 situated in the upper part of the cylinder 36 between the sealing members 40 and a check valve 42. The plunger 39 has in the side wall thereof an opening 43 which is in continuous communication with the space 44 within the cylinder 36 below the sealing members 40. This opening 43 communicates with an axial passage 45 which leads upwardly through the plunger 39 to the moving check valve 46 disposed at the upper end of the plunger 39. When the plunger moves upwardly from the position in which it is shown in Fig. 3, oil will be displaced upwardly from the pumping space 41 and through the standing valve 42 into the tubing string 16 by which the oil is carried to the exterior of the well 10. When the plunger 39 moves downward, the standing valve 42 closes and oil from the exterior of the pump 31 passes inward through the opening 37, the space 44, the opening 43 and the passage 45 of the plunger 39 into the pumping space 41.

The insulating connector 20 is disposed in the tubing string 16 above the level 14 of the oil, and from the shell 26 of the connector 20, an insulated electrical conductor 47 is carried down to the motor 32 of the pump unit 15. A special feature of the invention is that the reciprocating motor 32 is of induction type and therefore may be operated by power from an alternating current generator 48 which is connected in series with the upper ends of the casing 11 and the tubing string 16 by a conductor 49 and a conductor 50 having a control switch 51 therein, this conductor 50 being connected to the upper end of the tubing string 16 by a clamp 52. One of the terminals of the motor 32 is connected to the tubing string 16 by the insulated conductor 47 and the other terminal of the motor 32 is connected to the casing 11 by the bow springs 33, thereby forming an electric circuit including the motor 32, the source of electrical power 48 and the tubular metal mem-

bers in the well comprising the casing 11 and the tubing string 16. The tubing string 16 is insulated from the casing 11. For this purpose, cylindric bodies 50' of rubber, known to the art as tubing protectors, are disposed along the tubing string 16 at suitably spaced intervals.

The cooperation of parts disclosed makes possible the efficient pumping of oil from a well by electrical means, without the use of sucker rods, and without the disadvantages resulting from the use of sucker rods. A piston stroke of twenty feet or more may be employed.

Experience has shown that the use of electric cables extending down into the well from the top thereof is impractical, since the conditions under which cables are used results often in their injury and failure. Also, where two electrical conductors of opposite polarity contact a liquid of electrolytic character, there will be a flow of electric current through the liquid and if the current flow is maintained in one direction there will be an erosion of one of the conductors due to electrolysis. In the invention herein disclosed, the use in combination of an alternating current source and a reciprocating induction motor in the well to operate a pump which is suspended by a tube in the well, makes possible the use of the tube and the well casing as the electrical conductors supplying current to the reciprocating induction motor, thereby avoiding use of a cable extended down into the well and avoiding erosion of the tube or the well casing which occurs when direct current is employed under conditions such as set forth in the foregoing explanation.

I claim as my invention:

1. In a well pumping device of the character described operable from a source of alternating current electrical power situated at the top of the well having a metal casing set therein, the combination of: a tubing string of metal extended into the well; a reciprocating pump at the lower end of said tubing string having its outlet connected to the lower end of said tubing string; a reciprocating induction motor operatively connected to said reciprocating pump; and means electrically connecting said reciprocating motor and said source of alternating current electrical power in series with said tubing string and said casing.

2. In a well pumping device of the character described operable from a source of electrical power situated at the top of the well having a metal pipe string set therein, the combination of: a tubing string of metal in the well; a pump casing extending down from said tubing string, the upper end of said casing being connected to the lower end of said tubing string, there being an opening near the lower end of said casing connecting the interior of said casing with the space within the well; a tubular plunger vertically reciprocable in said casing, there being sealing means operative between said plunger and said casing above said opening of said casing and said plunger having a longitudinal passage, the lower portion of which is constructed and arranged to communicate with said opening of said casing; a check valve on said plunger for controlling flow through said passage of said plunger; a standing check valve in said casing for preventing reverse flow through said casing; a reciprocating electric motor operatively connected to the lower end of said plunger; means connecting said source of electric power to the upper ends of said tubing string and said pipe string; and means electri-

cally connecting said motor in series with said pipe string and said tubing string.

3. In a well pumping device of the character described operable from a source of electrical power situated at the top of the well having a metal pipe string set therein, the combination of: a tubing string of metal in the well; a pump casing extending down from said tubing string, the upper end of said casing being connected to the lower end of said tubing string, there being an opening near the lower end of said casing connecting the interior of said casing with the space within the well; a tubular plunger vertically reciprocable in said casing, there being packing means in said casing above said opening thereof making sealing engagement with the exterior of said plunger and said plunger having a longitudinal passage, the lower portion of which is constructed and arranged to communicate with said opening of said casing; a check valve on said plunger for controlling flow through said passage of said plunger; a standing check valve at the upper end of said casing for preventing reverse flow through said casing; a reciprocating electric motor operatively connected to the lower end of said plunger; means connecting said source of electric power to the upper ends of said tubing string and said pipe string; and means electrically connecting said motor in series with said pipe string and said tubing string.

4. In a pumping device for use in a well having a metal casing set therein and being operable from a source of electric power situated at the top of the well, the combination of: a tubing string of metal adapted to be extended into the well; a reciprocating pump hung from said tubing string and having its outlet connected to the lower end of said tubing string; a reciprocating electric motor operatively connected to said reciprocating pump; means connecting said source of electric power to the upper ends of said tubing string and said casing; means electrically insulating said tubing string from said casing and the exterior of said motor; contact means extending from said motor into engagement with the inner surface of said casing and making electrical connection of the operating parts of said motor with said casing; and insulated conductor means electrically connecting said tubing string with the operating parts of said motor.

5. In a pumping device for use in a well having a metal casing set therein and being operable from a source of alternating current electric power situated at the top of the well, the combination of: a tubing string of metal extended into the well; a reciprocating pump hung from and having its outlet connected to the lower end of said tubing string; a reciprocating induction motor operatively connected to said reciprocating pump; means connecting said source of electric power to the upper ends of said tubing string and casing; means electrically insulating said tubing string from said casing and the exterior of said motor; and means at the lower end of said tubing string electrically connecting the electrical parts of said motor in series with said casing and said tubing string.

6. In a pumping device for use in a well having a metal casing set therein and being operable from a source of alternating current electric power situated at the top of the well, the combination of: a tubing string of metal ex-

tended into the well; a pump at the lower end of said tubing string having its outlet connected to the lower end of said tubing string; an electric induction motor operatively connected to said pump means electrically insulating said tubing string from said casing; tubular insulator means above said motor insulating said tubing string from the exterior of said motor; means connecting said source of electric power to the upper portions of said tubing string and said casing; insulated conductor means connecting the lower portion of said tubing string with the electrical operating parts of said motor; and means electrically connecting said casing with the electrical operating parts of said motor.

7. In a pumping device for use in a well having a metal casing set therein and being operable from a source of electric power situated at the top of the well, the combination of: a tubing string of metal extended into the well; a pump at the lower end of said tubing string having its outlet connected to the lower end of said tubing string; an electric motor operatively connected to said pump; means electrically insulating said tubing string from said casing; tubular electrical insulator means above the liquid level in the well insulating said tubing string from the exterior of said motor; means connecting said source of electric power to the upper portions of said tubing string and said casing; insulated conductor means connecting the lower portion of said tubing string with the electrical operating parts of said motor; and means electrically connecting said casing with the electrical operating parts of said motor.

8. In a pumping device for use in a well having a metal casing set therein and being operable from a source of alternating current electric power situated at the top of the well, the combination of: a tubing string of metal adapted to be extended into the well; a pump at the lower end of said tubing string having its outlet connected to the lower end of said tubing string; an electric induction motor operatively connected to said pump; means on said tubing string for electrically insulating said tubing string from said casing; tubular insulator means above said motor insulating said tubing string from the exterior of said motor; said tubing string and said casing being adapted for connection to said source of electric power; insulated conductor means connected to the operating parts of said motor for connecting the lower portion of said tubing string with the electrical operating parts of said motor; and means connected to the operating parts of said motor for electrically connecting said casing with the electrical operating parts of said motor.
